UNITED STATES PATENT OFFICE

110,058

DESIGN FOR A HAT OR SIMILAR ARTICLE

Theodore J. Mundorff, Honolulu, Territory of Hawaii, assignor to Hawaiian Pineapple Company, Honolulu, Territory of Hawaii

Application October 16, 1937, Serial No. 72,241

Term of patent 14 years

To all whom it may concern:

Be it known that I, Theodore J. Mundorff, a citizen of the United States, and resident of Honolulu, in the city and county of Honolulu, Territory of Hawaii, have invented a new, original, and ornamental Design for a Hat or Similar Article of which the following is a specification, reference being had to the accompanying drawing forming part thereof.

I claim:

The ornamental design for a hat or similar article, as shown.

THEODORE J. MUNDORFF.
